LINE FUSE

Jess C. Rose, North Hollywood, Calif., assignor to
 J. G. McAlister, Inc., Los Angeles, Calif., a corporation of California

Application July 21, 1950, Serial No. 175,062

8 Claims. (Cl. 200—115.5)

1

This invention relates to a fused conductor connector, and more particularly to a connector between the free ends of two flexible conductor cables, which is both a connector and a load limiting circuit interrupter.

While the principles of the invention have application in a wide field of electrical circuits of many different types it has particular application to conditions such as obtain in moving picture and television studios. In these studios portable lights drawing currents of heavy amperage are used. Insulated flexible conductor cables lead from each lighting device to any one of a number of conveniently located buss bars or other current distributors, each distributor supplying current for a number of such lamps.

When, as is usually the case, the source of supply is from a center tapped single phase, 220 volt, transformer secondary, or a 110-220 volt, three wire direct current source, the three power line wires are connected to a three terminal distributor, to the outside legs of which the one wire of several of the two wire lamp cables are connected in approximate balance, the return wires of the cables from all the lamps being connected to the grounded middle leg of the distributor. These connections for the sake of rapidity of operation are made at the ends of each of the wires of the cables by terminal clamps. The three feed wires to the distributor are provided with circuit interrupters, either fuses or circuit breakers, of a size to protect the feeder lines from the load of all the lamp connections supplied by the distributor, but the protection of the individual lamps and individual lamp circuits from overloads caused by a short circuit in the lamp or between the two cable wires or otherwise, has presented a problem, of which this invention provides a solution.

The problem is made difficult by the conditions in the studios. The lamp cables from the buss bar or other distributor lie on the floor or are strung around the studio in frequently changed locations, usually in exposed positions where they are subject to trampling by vehicles and to other hard usage. If each lamp cable is a single two wire line without distributing connections to other lamps between the distributor and the one lamp, a separate cable is provided for each lamp. For proper overload protection of both the lamp and cable, the expensive provision of a number of individual fused outlets at each distributor becomes necessary in lieu of the customary rapidly operated and convenient clamps.

2

Since two single wire connections are made at the distributor for each lamp, it follows that if the system of terminal clamps is to be used, the logical place to fuse a lamp and lamp circuit is in the hot wire of the cable between the point at which it emerges from the cable and the terminal clamp which secures that wire to the buss bar terminal. The entire lamp circuit is then positively assured of overload protection.

10 This invention provides such a single wire combination connector and fuse for use close to the buss bar terminal. It is an object of the invention to provide a fused connector for a single flexible conductor, which shall be compact, readily operated, inexpensive of manufacture, capable of withstanding hard usage, and of simple construction.

It is another object to provide such a connector, which shall be quickly and inexpensively re-fused.

20 It is another object to provide such a connector constructed for ready assembly and disassembly with two slidably joined parts, the conductors of the connector being incapable of making a conducting contact until the two parts are joined together to provide a completely enclosed chamber for the fuse. This prevents the fuse from blowing, by reason of a pre-existing short circuit, as the two parts are being brought together, before they have moved toward each other sufficiently

25 to enclose the fuse, eliminating any fire hazard or injury to persons from flames blown outside the casing.

30 It is also an object of the invention to provide a fused connector which will completely enclose the fuse in a substantially gas tight chamber, but provide for slow escape of the gases, generated by the blowing of the fuse, over a baffled course so as to prevent the jetting of flame into the ambient.

35 The invention is herein disclosed as embodied in a fused connector for use with illuminating equipment of moving picture and television studios, but the principles of the invention are applicable wherever overload protection is desired.

40 Under different conditions, such protection may be conveniently associated with a line connector having utility other than as a mounting for the fuse element. Or a fused connector embodying the principles of the invention may be 45 used to protect both sides of the circuit, providing two connections and two fuses in the same casing. The invention, therefore, is not limited to the particular embodiment shown in the drawings and set forth in the following description, but 50 55 embraces any device which comes within the

spirit of the invention as defined in the appended claims.

In the drawings:

Figure 1 is a schematic view of a circuit embodying the invention. In this view the connector is shown in top plan view.

Figure 2 is an exploded view of the connector, showing the two parts of the casing pulled apart for examination or replacement of the fuse element.

Figure 3 is a vertical sectional view of the connector showing some parts in side elevation.

Figure 4 is a fragmentary top plan view of one end of the connector with the adjacent part of the casing horizontally sectioned to show the terminal structure within the casing.

Figure 5 is a fragmentary sectional view showing an alternative form of spacer ring.

Figure 6 is a sectional view taken along the line 6—6 of Figure 3.

In Figure 1 there is shown schematically a simple circuit in which the fused connector of this invention is used. A conductor 11 is connected to one of the terminals at one end of the buss bar 12 and to the connector 13 at its other end. Conductor 14 leads from the connector 13 to a lamp indicated diagrammatically at 15 and is sheathed in the cable 10 with a return conductor 16 which connects the lamp 15 with the center terminal of the buss bar, completing a standard 110 volt lamp circuit. The ends of conductors 11 and 16 are usually equipped with terminal clamps by which they may be rapidly connected or disconnected to the buss bar terminals. Conductors 14 and 16 at the lamp end of the cable 10 are plugged into a suitable terminal receptor on the lamp structure.

The fused connector 13 comprises a two part casing 17 made of insulating material and two terminal structures 18 and 19, the structure 18 being rigidly mounted and secured in the leftward casing part 20, and the structure 19 being rigidly mounted and secured in the rightward casing part 21.

The casing is in the general form of a hollow closed end cylinder, providing a cylindrical interior chamber in which the terminal structures, including the fuse element 22, are mechanically protected, are insulated electrically from surrounding objects outside the casing, and by which the fuse is prevented when it blows from setting fire to inflammable objects or injuring the studio personnel. The left end of the casing shell has secured to it by the retaining screws 23 an insulating end closure plug 24 which has a central aperture 25 for the reception of the insulated conductor 14. The right end of the casing shell similarly has secured to it by retaining screws 26 an insulating end closure plug 27 which has a central aperture 28 for the reception of the insulated conductor 11. The inner end of each closure plug is of reduced diameter to provide an annular recess over which the cylindrical shell of the casing fits, giving the casing a smoothly contoured cylindrical exterior surface. The closure plugs are rounded at their outer ends, this feature and the smooth exterior surface of the shell enabling the connector to be dragged over the studio floor and other surfaces without danger of being caught and torn loose from the conductors.

The rightward part 30 of the shell has a telescopically sliding connecting joint at 31 with the rightward part 32. The outside diameters of the parts are the same. The rightward part 32 has an inwardly projecting skirt 33, providing a shoulder 34, against which the rightward end part of the shell abuts when the two parts are pushed into

home position. The retaining screw 35 holds them immovably in this position.

The leftward terminal structure 18 is permanently and rigidly mounted on the leftward part 29 of the casing and when the two casing parts are pulled apart at the joint 31, this terminal structure stays intact in leftward casing part 20. This terminal structure comprises a socket member 36 of brass or other conducting material which is formed with a central recess 37 on its left end into which the wire core of the conductor 14 is soldered, and with a fingered socket 38 on its right end for the reception of the contact pin 39 of the rightward terminal structure. The leftward terminal structure is completed by the ring 40, preferably of insulating material, which is fastened to the socket member 36 by the screw 41, this ring being in turn secured to the casing shell part 30.

The rightward terminal structure 19 comprises the contact pin member 42, the conductor connecting member 43, both of brass or the like, and a connecting bridge or dielectric frame member 44 of insulating material, which is rigidly secured by the two bolts 45 to the two lugs 46 respectively on the juxtaposed ends of the pin member 42 and cable connecting member 43. The fuse element 47 is also secured or mounted by means of these bolts to the lugs 46 but on the side of the lugs opposite the bridge 44. The lugs are preferably threaded to receive the threaded shanks of the bolts. Since each nut is disposed at the fuse end of its bolt and the bolts are held in position by reason of their threaded relation to the lugs, this mounting means permits the nuts to be removed and the fuse replaced without disassembling the pin member 42, the bridge or frame 44 and the conductor connecting member 43, simplifying and shortening the re-fusing operation.

The contact pin member 42 carries the contact pin 39 sized to snugly mate with the fingered socket 38. The socket fingers are rounded at their outer ends to facilitate the entry of the pin 39. The contact pin member 42 is centered in the leftward shell part 20 by an insulating ring 49 secured to the pin member by a set screw 50. This ring slides along the bore surface of the shell part 20 and is of a diameter to give it a slight clearance with respect to this bore surface for two reasons. The gases formed when the fuse blows may escape through this clearance to the chamber to the left of the ring, from which chamber the gases may slowly bleed through very small bleeder holes 52 in the casing shell around this chamber. The second advantage will appear from a consideration of the manner in which terminal structure 19 is mounted in the rightward shell part 21.

The conductor connecting member 43 is soldered to the wire core of the conductor 11 in the same manner as has been described above for conductor 14. The member 43 has fastened to it an insulating ring 53 by the set screw 54, which in turn is secured to the rightward casing shell portion by the retaining screw 55. It is then clear that the casing part 21 and the entire rightward terminal structure 19 from the contact pin 39 to the conductor 11, including the rings 49 and 53, the fuse 47, bridge 44 and conductor 11 move bodily as a single substantially rigid subassembly, when the retaining screw 35 is removed and the two parts of the casing are pulled apart. Similarly the leftward terminal structure moves with

its several associated parts as a single subassembly with the leftward casing part 20.

These two subassemblies are related to each other in the same fashion as are the two parts of an ordinary plug and socket connector, and the addition of the fuse to one subassembly does not destroy the similarity. The fuse and fuse holder are secured to, and are removable with, the one end of the connector, a feature of construction which simplifies the handling of the device when a fuse is to be replaced.

For easier fabrication and greater strength the retaining screw 35 is of a length to be threaded into the ring 53. When the two parts of the connector are moved toward each other for final assembly, the pin 39 and ring 49 are first to enter the shell of the leftward part of the connector. The slight clearance between the ring 49 and the leftward shell facilitates the entry movement. Since the length 54' of the telescopic joint between the shell parts is greater than the distance 55' between the extreme left end of the contact pin 39 and the extreme right end of the fingered socket 38, the chamber surrounding the fuse between rings 49 and 53 will be formed and closed prior to the making of contact between the contact pin and fingered socket. If, then, there is an undiscovered short which has not been corrected at the time the casing parts are being slid into their home position, the fuse will blow, but this will not happen until the fuse chamber has been formed, and the danger of fire to surrounding objects and injury to the operator are thereby eliminated.

Figure 5 shows a modification of the contact pin member. Instead of the single insulating ring 49 of Figure 3, a triple finned brass ring 56 is formed integrally with the remainder of the contact pin member. The rim surfaces of this triple ring 56 have a substantially close sliding fit with the bore surface of the casing. Small drilled bleeder holes 57 are then provided transversely through the rings, the holes in one ring being in staggered relation to the holes in the other rings. The rings then act like baffle plates to break up jets of flame from a blown fuse, while yet permitting the passage of the gases from the disintegrated fuse through the rings to relieve the gas pressure in the inner fuse chamber.

The foregoing description of the fused connector reveals its uses, the manner in which it is re-fused and the advantages which come from its incorporation in an electrical circuit in the way described.

I claim:

1. A connector for connecting two insulated electrical conductors comprising: a first rigidly and permanently assembled terminal fixture mechanically and electrically adapted to be secured to a free end of one of said conductors; a second rigidly and permanently assembled terminal fixture adapted to be mechanically and electrically secured to the free end of the other of said conductors; said fixtures each comprising a casing tube of insulating material having an aperture at its outer end, and a conductor terminal structure permanently and rigidly secured within the tube, the casing tubes slidably telescopically engaging each other at their inner open ends, and providing a substantially gas tight envelope of insulating material for the terminal structures, said free ends of the insulated conductors entering the casing tubes through the apertured outer ends thereof respectively for securing to the terminal structures respective-

ly, the terminal structures having pin and socket electrical contacts for engagement with each other when the tubes are moved toward one another into telescoped position, and one of the terminal structures having mounting means interposed in its conductance path for supporting an overload fuse; interengaging means on the tubes and terminal structures for constraining the fixtures and consequently the tubes and terminal structures to move in parallel straight lines, each with respect to the other, while they are being telescopically joined; and means for securely fastening the casing tubes together when telescopically joined.

2. A connector for use between the ends of two conductors, comprising: a two-part tubular casing, each part having a closed end, apertured to pass one of the conductors, and the two parts having a sliding gas-tight telescopic joint for holding them in relatively fixed assembled position, a first terminal structure fixedly mounted and fastened in one casing part and arranged for securing to its associated conductor end, a contact element on said first terminal structure, a second terminal structure having a rearward position fixedly mounted and fastened in the other casing part, said second terminal structure having a forward portion including a contact element for making contact with said contact element on said first terminal structure when the two casing parts are in assembled position, a dielectric frame member included in said second terminal structure connecting said forward and rearward portions, mounting means on said forward and rearward portions for connecting a fuse therebetween, said other casing part having a length sufficient to enclose the entire length of space between said mounting means when the two casing parts are assembled, the two terminal structures being mounted in their respective casing parts at such positions therealong that when the casing parts are placed in the initial position of their sliding telescopic joint the contact of the second terminal structure is out of electrical contact with the contact of the first terminal structure, and when the two casing parts are in the home position of their joint the contact element of the second terminal structure is in electrical contact with the contact of the first terminal structure.

3. A connector for use between the ends of two conductors, comprising: a two-part tubular casing, each part having a closed end, apertured to pass one of the conductors, and the two parts having a sliding gas-tight telescopic joint for holding them in relatively fixed assembled position, a first terminal structure fixedly mounted and fastened in one casing part and arranged for securing to its associated conductor end, a contact element on said first terminal structure, a second terminal structure having a rearward position fixedly mounted and fastened in the other casing part, said second terminal structure having a forward portion including a contact element for making contact with said contact element on said first terminal structure when the two casing parts are in assembled position, a dielectric frame member included in said second terminal structure connecting said forward and rearward positions, mounting means at said forward and rearward positions for connecting a fuse therebetween, said terminal structures including annular spacers rigidly related to the terminal structures and extending outwardly to the bore surface of the casing, the first terminal structure having

a spacer intermediate its connection to its associated conductor end and its place of contact with the second terminal structure, and the second terminal structure having one spacer adjacent its contact element and the other spacer adjacent its connection with its associated conductor end, whereby a substantially gas-tight chamber is provided for the contacting connection between the two terminal structures, and another substantially gas-tight chamber is provided for the space between said mounting means.

4. The combination defined in claim 3, in which transverse gas bleeder holes are formed in the one spacer of the second terminal structure, and gas bleeder holes are provided in the casing between the spacer of the first terminal structure and the one spacer of the second terminal structure.

5. The combination defined in claim 3, in which the one spacer of the second terminal structure has a plurality of proximately adjacent, spaced, parallel ring-like walls, and in which transverse gas bleeder holes are formed in each of said walls, the holes in one wall being staggered with respect to the holes in an adjoining wall, whereby when the fuse blows flame will not pass through the said parallel walls in single straight jets.

6. The combination defined in claim 5, in which further gas bleeder holes is provided in the casing between the spacer of the first terminal structure and the one spacer of the second terminal structure.

7. The combination defined in claim 3, in which the casing is of an insulating material, and the ends thereof are centrally formed with the said apertures for passage of the conductor ends, and the said terminal structures are each provided with a socket at its extreme outer end for soldering the associated conductor end.

8. The combination defined in claim 3, in which

- 5 the one casing part extends inwardly a distance sufficient to enclose the entire length of space between said mounting means when the two parts are in assembled relationship, and the second part has a telescopic gas-tight joint with the first part, the terminal structures being mounted in their respective casing parts at such positions along said casing parts that when the two casing parts are placed in the initial position of their telescopic joint the contact element of the second terminal structure is out of electrical contact with the first terminal structure, and when the two casing parts are in the home position of their joint the contact element of the second terminal structure is in electrical contact with the first terminal structure, and in which the first terminal structure and the contact element of the second terminal structure are formed with pin and socket mating elements, the one spacer of the second terminal structure is of a diameter to slightly clear the bore surface of the casing, the other spacer of the second terminal structure engages the bore surface of the second casing part, both casing parts, including their ends are of dielectric material, the apertures for the conductor ends are disposed centrally of the casing ends, and the said terminal structures are each formed with sockets at their extreme outer ends for soldering their associated flexible conductor ends to said terminal structures.
